[57] CLAIM

The ornamental design for a room heat recirculator, as shown.

DESCRIPTION

FIG. 1 is a front elevational view of a room heat recirculator, showing my new design;

FIG. 2 is a rear elevational view thereof;

FIG. 3 is a side elevational view thereof, the opposite side being a mirror image of the side shown;

FIG. 4 is a top plan view thereof; the bottom being the same as the top shown; and

FIG. 5 is a cross sectional view taken on line 5—5 of FIG. 1.

FIG. 5.

FIG. 4.

FIG. 1.

FIG. 2.

FIG. 3.
